UNITED STATES PATENT OFFICE.

JOHN SNELL CHENHALLS, OF PLYMOUTH, ENGLAND.

OIL-BURNER.

SPECIFICATION forming part of Letters Patent No. 705,820, dated July 29, 1902.

Application filed February 28, 1902. Serial No. 96,168. (No model.)

To all whom it may concern:

Be it known that I, JOHN SNELL CHENHALLS, engineer, a subject of the King of England, residing at 59 Ebrington street, Plymouth, in 5 the county of Devon, England, have invented a certain new and useful Improvement in Oil-Burners, of which the following is a full, clear, and exact description, and for which I have applied for Letters Patent in Great 10 Britain, No. 26,142, filed December 21, 1901.

This invention relates to an improved oil-burner for heating generators and the like.

It consists of a device in which the oil is mingled with exhaust-steam or other waste 15 heat and conducted to the flame of a pilot-burner, and thus heated before being burned, as will be hereinafter described. These vapors or gases contain a considerable quantity of thermal energy, which I propose to 20 utilize in the present invention.

The invention is illustrated upon the accompanying drawing, which shows the burner in elevation, part section.

The hydrocarbon is fed to the burner 25 through a pipe *a*, having a check-valve *f*, as shown. This pipe *a* is connected to a pipe *b* by means of a T-piece, and through the pipe *b* exhaust-steam or other waste heat (such as furnace-gases) is admitted. The pipe *b* is 30 passed through the casing *h* of a generator and within the same is formed into a coil *c*, which, after extending into the generator for a suitable distance, is returned upon itself to 35 form an outer coil *e*, preferably concentric with the first, *c*. The pipe then passes out through the casing *h* and is connected to a nozzle *d*. A pilot-burner *g*, as shown in dotted lines, is arranged at a suitable position within the generator to face the coils *c* *e* and 40 to ignite the mixture from the nozzle *d*. This pilot-burner may be of any ordinary type.

The oil, which is supplied to the pipe *a* from a tank or other receptacle, may be pre-

liminarily vaporized—for instance, by heating the pipe by means of the exhaust or some 45 portion of the exhaust or otherwise.

The exhaust-steam supplied to the pipe *b* may be superheated or dried in any ordinary manner before reaching the union with pipe *a*.

The exhaust-steam or other waste heat is 50 admitted into pipe *b*, carries along with it a mixture of oil or oil-vapor from the pipe *a* into the coil *c* and the coil *e*, and the mixture is burned at the nozzle or burner proper, *d*. It will be seen that the coils *c* and *e* are ar- 55 ranged about the zone of the flame of the burner, which consequently heats the mixture in the coils before it is burned.

The pipe *a* after being formed into a coil within the generator may be brought directly 60 back to the nozzle *d* without forming a second coil. Further, the coils *c* *e* may extend to and around the pilot-burner *g*, if desired.

The oxygen of the steam combines with the carbon of the oil and hydrogen thus liberated 65 burns together with the hydrogen in the oil together giving a very hot flame as is well known.

Having thus described my invention, what I claim as such, and desire to secure by Letters 70 Patent, is—

In combination, an oil-pipe, an exhaust-pipe, a connection between the said pipes, a check-valve in said connection closing toward the oil-pipe, a pipe *c* connecting with the exhaust-steam pipe *b* and comprising inner and outer coils, the outer coil having a vapor-discharge nozzle arranged to discharge vapor centrally through the coil, substantially as described. 75

In witness whereof I have hereunto set my hand in presence of two witnesses.

JOHN SNELL CHENHALLS.
